UNITED STATES PATENT OFFICE.

FRIEDRICH OSCAR SCHNELLE, OF FRANKFORT-ON-THE-MAIN, GERMANY.

ELECTRICAL SEPARATOR.

1,071,354.

Specification of Letters Patent. Patented Aug. 26, 1913.

Application filed June 15, 1904. Serial No. 212,665.

To all whom it may concern:

Be it known that I, FRIEDRICH OSCAR SCHNELLE, electrical engineer, residing at 18 Guiollettstrasse, Frankfort-on-the-Main, 5 Germany, have invented new and useful Improvements in Electrical Separators, of which the following is a specification.

This invention relates to the dry separation or concentration of comminuted, granular materials, ores, minerals and similar products whose individual particles or grains differ in their susceptibility to electrostatic charges. Its object is to carry out the separation in a simple and effective way 15 fit for industrial application on a large scale.

I am aware that it has been proposed to utilize both electrostatic attraction and repulsion for separating commingled materials and that various forms of apparatus 20 have been designed for that purpose, but owing to the difficulty of obtaining a clean separation and to the small output and unreliable working of the machinery electric separation has found but a very limited 25 commercial application. These difficulties are overcome by the present invention according to which the separation is effected under essentially different conditions as will be more fully explained hereinafter.

The physical foundation of my invention 30 I understand to be the generation of an intense electrostatic field of force upon a comparatively narrow zone, preferably at or near the borders or edges of a suitably 35 shaped body, to which an electrostatic charge may be imparted either by conduction or induction. I judge this from the fact that particles of commingled material spread over the upper surface of such a body appear to be unaffected by a charge of suitable 40 potential as long as they remain at a certain distance—say about one inch—from the “active” zone. The kinetic action of the charge upon the particles being thus practically confined to a relatively narrow margin 45 a distinct differentiation between the particles to be separated is effected by moving the mixture upon the said surface into and through the intense field preferably 50 surrounding its border or edge. Here the separation occurs. The particles of higher susceptibility to the charge upon entering the zone of action are thrown off the surface in the direction of the electrostatic lines of 55 force emanating from its border; the particles less susceptible to the influence of the

field are but slightly affected by the charge and drop off the surface closer by the edge. I have found that the effect is the more marked the closer the said zone of action is 60 confined to the border or edge of the surface upon which the material is spread out.

The manner in which the commingled materials may be fed upon the surface of the separating body, the means by which they 65 may be conveyed or transported to the active zone, separated and collected separately will be readily understood by reference to the annexed drawings, in which—

Figure 1 is a vertical central section 70 through a complete separating machine. Fig. 2 is a diagrammatic sketch of a combination of several apparatuses similar to Fig. 1, Fig. 3 is a front view of another type of separator, Fig. 4 is a vertical section 75 along the broken line X—X of the apparatus shown in Fig. 3.

Like letters refer to similar parts throughout the several drawings.

Referring to Fig. 1, A represents a conical 80 feed hopper to which the separating body B, in the shape of a flat cone is rigidly attached. The hopper A is supported by 3 rollers L grooved or corrugated around their circumference as indicated in the drawing. 85 The rollers L are carried by the ring R which is supported by 3 or more columns S resting upon the wooden frame C. One of the rollers L is driven by a pulley P thereby causing the hopper A together with the cone B to rotate about the common axis. The corrugations of the rollers L superpose 90 upon the slow rotation a quick vibratory or shaking motion, which will be referred to more particularly hereinafter. Under and 95 surrounding the cone B is a system of conical receptacles D and E provided with outlets emptying into the boxes I and II. The truncated conical surface Z indicated by dotted lines as surrounding the separator 100 cone B will be hereinafter referred to. The columns S are to be of insulating material such as hard rubber or glass all other parts may consist wholly or partly of metal (unless otherwise stated). The ring R is connected to the one terminal of a suitable 105 source of high potential electricity as for instance an electrostatic machine. The charge is transmitted by means of the rollers L to the hopper A and to the cone B. 110 The other pole of the generating apparatus may be grounded and correspondingly also

the receptacle E surrounding the cone B. From this arrangement it is evident that an electrostatic field is generated between the rim of the cone B and the surrounding parts of the receiving hoppers, having its greatest intensity at the outer circumference of the cone B.

The operation of this machine is as follows: When the pulley P is driven in either direction the vibratory motion imparted to the hopper A and the cone B causes the material contained in the hopper A to spread out over the surface of the cone B in an evenly distributed film. Upon approaching the rim of the cone B the separation takes place, as indicated in the figure and in accordance with the general observations above described. The different products are caught by the receptacles D and E and thence emptied into the boxes I and II respectively, the box I receiving the strongly "excitable" material, the box II the more indifferent particles, *i. e.* those which are less susceptible to electrification. The "active" zone of the separating body B may be still more intensified or condensed at the rim or edge by opposing to the same an annular or conical conductor such as indicated by Z, this conductor being of different potential to that of the cone B. The conductor Z may be charged with the opposite polarity to that of the cone B by connection with the other pole of the generator used for charging the cone B. In these cases however care must be taken that this conical ring does not disturb the path of the falling materials which would be the case if this body was laid too closely around or above the rim of the cone B, for then the particles of higher susceptibility would be strongly attracted by the said "opposite" pole and after contacting with the same be rejected toward the inner collecting hopper D thereby disturbing the separation and spoiling the products. This is avoided by calling the force of gravity into play in directing the path of the falling materials. It is important, however, to note that while gravity coacts with the kinetic action due to the electrostatic field in determining the curve followed by the stream of falling particles, deviating them from the direction of the electrostatic lines of force, the separation itself is essentially determined by the specific action of the electrostatic charge. In case an insulated conductor as indicated by Z charged with a suitable potential is used as an "opposing pole" to the rim of the cone B, the latter may also be charged by induction from Z and in this case the hopper A carrying the cone B would not need to be insulated from the earth.

In regard to the shape of the cone B it is to be noted, that its elements need not be straight lines but are by preference curves, flattening out toward the circumference. It

is further to be noted that the rim must not be sharp-edged in order to produce the desired field concentration for giving the best results, but according to my experiences it is rather advantageous to give the same a more or less rounded-off profile.

While I have found the shape of the flattened cone B as represented in the drawing (Fig. 1) in combination with its vibratory motion of special advantage for an even distribution of the material upon its surface, and for presenting the particles to be separated to the active zone or rim, I wish it to be understood that the shape of this surface may be varied in many ways without departing from the spirit of this invention. Thus, for instance, the inclination of the conical surface may be such that the material will glide down by its own weight without any motion being imparted to the said surface.

Fig. 2 shows a combination of three separating cones B B¹ B² mounted upon a common shaft by which a suitable motion as well as the electric charge may be transmitted to the cones. The cone B receives the commingled material directly from the hopper A, after separating out the majority of particles of highest susceptibility, the "indifferent" material together with "middlings" and the remaining portion of highly susceptible material are subjected to a second separation by means of B¹ and likewise to another "repetition" upon B² the final products being collected from D² and E as "I" and "II" similarly to Fig. 1. It is evident that by such a repetition the capacity of the apparatus can be raised and the quality of the product improved.

Figs. 3 and 4 show a "linear" type of separator likewise embodying my invention. Instead of the conical hopper in the previous figures a long V-shaped trough like hopper A' is used here to receive the material to be separated. A narrow opening or slot passes through the bottom of the hopper A' from end to end of the same. Underneath this slot is a rectangular bar T supported by the two levers K. Some distance below T is a small trough V and immediately under the same flat bar B³ slanting to both sides and rounded off at the edges. The trough V as well as the flat bar B³ are likewise fastened, at each end to one of the levers K. The latter are here supposed to be of insulating material, and are pivotally supported by the pins Q projecting from the end walls of the hopper A'. In order to impart to these levers an oscillatory or swinging motion they are connected by pins O to bars J engaging with the two eccentric pins Y set off a common shaft driven by the pulley P. The hopper A' is supported by the wooden frame C which also carries the bearings for the driving

shaft and the pulley P. Below the flat bar B³ are the receiving boxes I, II, I inclosed by adjustable partitions F and side walls H. The parts V and B³ are to be connected to the one pole of a generator of high tension electricity, while the receiving receptacles and all other parts of the apparatus may be grounded or connected with the other pole of the generator. The action of this machine is essentially analogous to that of the "annular" type previously described. It is evident that the oscillatory motion imparted to the bar T by the levers K causes the granular material contained in the hopper A' to be fed in a thin film from either side into the trough V and thence on to the upper surface of B³. The vertical distance through which the material has to fall is determined in this case by the necessity of insulating the parts V and B³ from the downwardly projecting portions of the hopper A'. In all other respects the separating process is analogous to that above described and will be readily understood from the drawing Fig. 3.

Modifications corresponding to those described in connection with Figs. 1 and 2 may also be executed in the "linear" form, and all that has been said in regard to the electrical and mechanical functions of the cone B (Fig. 1) similarly applies to the linear separating body B³, (Fig. 3).

Other modifications of the apparatus will readily suggest themselves, thus the laterally oscillating or swinging motion given to the parts K, V and B³, Fig. 3 may be replaced by a longitudinally reciprocating movement which would again suggest a common actuating mechanism for a number of superposed "linear" separating devices similar to Fig. 2. My invention, therefore, is not limited to the special forms illustrated by the annexed drawings.

Now what I claim and desire to secure by Letters Patent is the following:

1. An electrostatic separator, having an inclined conductor provided with a border edge or verge, means for charging said conductor electrostatically, means for feeding a commingled mass of particles of different susceptibilities to electrical repulsion to said conductor, means for causing said particles to pass on uninterruptedly over the upper surface of the conductor until they reach the said border edge or verge, whereby the mass as it passes over the edge or verge is subjected to the separating action of the intense zone of repulsion at said border edge just as the mass is about to drop therefrom, and a dividing and guiding barrier interposed between the paths of outward trajectory of the separated particles of different susceptibilities to electrical repulsion as they pass over said edge or verge, said barrier being likewise interposed in the path of possible subsequent commingling of the separated particles; substantially as described.

2. An electrostatic separator, having an inclined conductor provided with a border edge or verge having a surface rounded in cross-section, means for charging said conductor electrostatically, means for feeding a commingled mass of particles of different susceptibilities to electrical repulsion to said conductor, means for causing said particles to pass on uninterruptedly over the upper surface of the conductor until they reach the said border edge or verge, whereby the mass as it passes over the edge or verge is subjected to the separating action of the intense zone of repulsion at said border edge just as the mass is about to drop therefrom, and a dividing and guiding barrier interposed between the paths of outward trajectory of the separated particles of different susceptibilities to electrical repulsion as they pass over said edge or verge, said barrier being likewise interposed in the path of possible subsequent commingling of the separated particles; substantially as described.

3. An electrostatic separator, having an inclined conductor provided with a border edge or verge, means for imparting to said conductor an electrostatic charge of a given sign, means for feeding a commingled mass of particles of different susceptibilities to electrical repulsion to said conductor, means for subjecting the mass to the simultaneous action of gravity and of said edge as the mass passes over the latter, an outlying conductor and means for imparting to it an electrostatic charge of opposite sign, said outlying conductor being within a sufficient range to augment the intensity of the separating field at the said edge or verge of the inclined conductor, and a separating and guiding barrier interposed between the paths of trajectory of the separated particles of different susceptibilities to electrical repulsion as they pass over said edge or verge, said barrier being likewise interposed in the path of possible subsequent commingling of the separated particles; substantially as described.

4. An electrostatic separator, comprising a conical conductor, a hopper for supplying the particles to be separated to the apex of said conical conductor, means for rotating the conical conductor and its supply hopper, means for imparting an electrostatic charge to said conical conductor, and means for separately collecting the separated grades of material; substantially as described.

5. An electrostatic separator, comprising a conical conductor, a hopper for supplying the particles to be separated to the apex of said conical conductor, means for imparting an electrostatic charge of a given sign to

said conical conductor, an outlying cylindrical conductor and means for imparting to it an electrostatic charge of opposite sign, and means for separately collecting the separated grades of material; substantially as described.

6. An electrostatic separator, comprising a conical conductor, a hopper for supplying the particles to be separated to the apex of 10 said conical conductor, means for imparting an electrostatic charge to said conical conductor, and a divider projecting into the trajectories of material repelled from the verge of the base of the cone; substantially 15 as described.

7. An electrostatic separator, comprising a conical conductor, a hopper for supplying the particles to be separated to the apex of

said conical conductor, means for imparting an electrostatic charge of a given sign to 20 said conical conductor, an outlying cylindrical conductor and means for imparting to it an electrostatic charge of opposite sign, and a divider projecting into the trajectories of material repelled from the verge at 25 the base of the cone; substantially as described.

In testimony that I claim the foregoing as my invention, I have signed my name in presence of two witnesses, this 31st day of 20 May 1904.

FRIEDRICH OSCAR SCHNELLE.
